COMBINED CAKE CUTTER AND SERVER

Arthur Salm, Chicago, Ill., assignor to Arthur Salm Inc.,
Chicago, Ill., a corporation of Illinois

Application November 7, 1956, Serial No. 43,688

Term of patent 14 years

(Cl. D22—3)

Fig. 1 is a face view of a combined cake cutter and server showing my new design;

Fig. 2 is a side view of the combined cake cutter and server of Fig. 1;

Fig. 3 is an end view of the combined cake cutter and server of Fig. 1; and

Fig. 4 is a transverse sectional view of the blade portion of the combined cake cutter and server taken on the line 4—4 of Fig. 1.

I claim:

The ornamental design for a combined cake cutter and server, substantially as shown.
